SCARF

Gladys Whitcomb Geissmann, New York, N. Y.,
assignor to Merry Hull & Company, New York,
N. Y., a partnership

Application January 5, 1944, Serial No. 517,029

4 Claims. (Cl. 2-91)

1

This invention relates to neckwear and relates particularly to improved forms of scarves of a type to be worn around the neck.

Prior neck scarves are usually rectangular, square or triangular in shape and are made of many different types of material. All such scarves have, in common, the characteristic of being cut from or formed of a flat piece of material.

Inasmuch as the human neck and shoulders are not polygonal or flat, the shape of the conventional scarf results in a number of disadvantages from the standpoint of protection and appearance.

A conventional triangular scarf, for example, is usually placed across the shoulders and wrapped around the neck with the apex of the triangle disposed somewhere in the vicinity of the shoulder blades and with the ends or corners of the scarf crossing the chest and throat. Inasmuch as this scarf must partake of a series of intersecting curves of different length and radii in assuming this position, it either has a tendency to wrinkle and bunch up around the back of the neck causing discomfort and an unkempt appearance or the ends of the scarf tend to slide apart, become disarranged and expose the throat and chest.

The square type of scarf has the same disadvantages as the triangular type inasmuch as when it is worn as a square even more material tends to wrinkle and bunch up around the back of the neck and it is even more difficult to retain in place. Moreover, the pointed ends, either crossed or knotted, do not furnish full protection for the throat and chest.

The rectangular scarf is similarly unsatisfactory and when it is looped over in front, like an ascot tie, as is sometimes the case, it draws the entire width of the scarf into a narrow thick bunch around the neck, leaving spaces between the scarf and coat collar and either side of the ascot. In other words, it is mechanically impossible to cover the throat and the chest by means of a straight piece of fabric that is looped into an ascot. When merely crossed over the chin, a rectangular piece scarf does not protect the throat, rides up on the back of the neck and does not stay in place.

The present invention has as an object the provision of a scarf which overcomes the disadvantages of the prior types of scarves referred to above.

Another object of the invention is to provide a scarf which is fitted to the neck and shoulders, and, therefore, does not bunch up at the back

2

of the neck, cause discomfort, displace the coat collar, and expose part of the throat and chest.

Another object of the invention is to provide a scarf which is so shaped and arranged that the depending ends of the scarf, when overlapped over the chest, will remain in such overlapped position in a self-draped manner, thereby providing adequate protection for the throat and the chest and maintaining a neat and well-groomed appearance.

Other objects of the invention will become apparent from the following description of a typical form of scarf embodying the present invention.

In accordance with the present invention, I provide a scarf which is formed of a plurality of shaped sections of fabric, fur or the like in which the back yoke section of the scarf is shaped to conform to the shape of the shoulders where the shoulder curve and neck curve intersect and the ends or foreparts of the scarf are joined to the yoke in such a manner that the scarf curves smoothly and naturally up on the neck and outwardly over the shoulders.

More particularly, the center portion or yoke of the scarf is formed of one or more shaped sections of material having suitably curved upper, lower and side or end edges so that it fits closely and conforms to the back of the neck and the top of the shoulders. The end portions of the scarf are formed of shaped pieces of material, which are joined to the lateral edges of the center or yoke portion of the scarf in such relationship that they normally tend to drape downwardly and across the chest in overlapping relationship.

Scarves of the type embodying the present invention have numerous advantages not obtainable with the prior art scarves. Inasmuch as the center or yoke portion of the scarf is fitted to the curves of the neck, it does not bunch up and does not displace the collar of a coat worn over the scarf. Because of this better fit, the material in this portion of the scarf can be thicker and warmer without being uncomfortable and unattractive and without displacing the coat collar to as great an extent as a conventional scarf formed of lighter material. Moreover, such smoothly draped and fitted scarves do not distort the appearance of the shoulders of a coat worn over the scarf. In addition, the portion of the scarf that passes around the sides and front of the neck will lie smoothly around the neck and will remain in position so that adequate covering of the neck can be obtained. The scarf also has the advantage of affording maximum pro-

tection to the throat and the chest inasmuch as its normal tendency is to stay in throat and chest covering position, rather than to fall away from the throat and chest.

In addition to the practical advantages of scarves of the type embodying the present invention, these scarves lend themselves to new combinations of fabrics and colors which render them particularly attractive in appearance. Thus, the scarf may be formed of one type of material such as, for example, velvet or silk and may be lined with another type of material of the same or contrasting color, making a reversible scarf, thus giving an economic as well as a decorative advantage. Such scarves thus may be reversed readily to match or contrast with other garments. If desired, the portion of the scarf which covers the back of the neck may be of a different material or a different color than the portion which is disposed over the chest and shoulders. Inasmuch as the scarf fits snugly, it can be formed of a light weight or relatively short pile fur, if desired, without excessively displacing or destroying the fit of a garment worn thereover.

For a better understanding of the present invention, reference may be had to the accompanying drawing, in which:

Figures 1a to 1d are plan views of the sections of material making up a typical form of scarf embodying the present invention;

Figure 1e is a plan view of a modified form of center yoke portion;

Figure 2 is a plan view of the scarf;

Figure 3 is a front view of the scarf illustrating the manner in which it drapes around the neck and over the shoulders and chest; and

Figure 4 is a rear view of the scarf.

As illustrated in Figures 1a to 1d, a scarf of the type embodying the present invention may be suitably formed of four sections of material 10, 11, 12 and 13, such as, for example, fabrics, fur or the like. The sections 10 and 11 are substantially mirror images of each other and are generally of four-edged shape in which each of the edges is curved. As illustrated, the upper edge 10a of the section 10 is convexly curved on a relatively long arc, while the lower edge 10b is a shorter concave arc on a slightly longer radius than the upper edge 10a. The inner edge 10c of the section 10 is concavely curved on an arc of relatively long radius, while the opposite edge 10d is substantially straight for a major portion of its length and then sharply concavely curved on down to its junction with the edge 10b.

The section 11 is similarly shaped, but, as indicated above, is a mirror image of the section 10. The edges of the section 11 corresponding to the edges 10a, 10b, 10c and 10d of the section 10 are identified as the edges 11a, 11b, 11c and 11d.

When assembling the scarf, the edges 10c and 11c are joined by means of a suitable seam 14, as shown more particularly in Figures 2 and 4 of the drawing, thereby aligning the curved edges 10a and 11a in a substantially continuous arc and aligning the edges 10b and 11b to form a shorter arc at the opposite edge of the scarf. Inasmuch as the edges 10c and 11c are curved slightly, the back of the assembled sections or yoke will be rendered slightly concave to correspond to the curvature of the junction zone of the back and the neck. This back section or yoke of the scarf, therefore, normally tends to assume a convex curvature from end to end and a concave curvature from top to bottom. These in-

tersecting curvatures tend to maintain the yoke in close contact with the neck and shoulders. While a somewhat better fit is attained by forming the yoke in two sections as described above, it will be understood that the yoke may be formed from one piece of material 10' generally of the outline produced by joining the sections 10 and 11, as shown in Figure 1e. Of course, the single piece yoke does not have the transverse concave curvature described above, but this is not serious when the yoke is made relatively narrower and is not intended to extend up as high on the back of the neck. If desired, a one-piece yoke can be used and a variable width tuck 15 may be taken in the center of the yoke 10' along the dotted lines to impart the desired transverse curvature to the yoke.

The depending front or end portions of the scarf are formed of the two sections 12 and 13 of fabric or other material. These sections are provided with downwardly and outwardly inclined upper edges 12a and 13a and inner edges 12b and 13b that are curved upwardly and inwardly toward the inclined edges 12a, 13a, respectively. The inner edges 12b and 13b are straight at their lower ends. As illustrated, the sections 12 and 13 have substantially straight outer edges 12c and 13c and straight lower edges 12d and 13d.

The length of the edges 12a and 13a may be the same as the overall length of the edges 10d and 11d of the sections 10 and 11 of the scarf, or if it is desired to have a pleated or gathered scarf, as illustrated in the figures of the drawing, the edges 12a and 13a may be somewhat longer than the edges 10d and 11d. The edge 12a of the section 12 is joined to the edge 10d of the section 10, while the edge 13a of the section 13 is joined to the edge 11d of the section 11, as best shown in Figure 2 of the drawing.

Referring now to Figure 2, it will be apparent that when the scarf is laid out with the sections 12 and 13 in alignment and substantially flat, the yoke formed by the center sections 10 and 11 will have a tendency to wrinkle inasmuch as it is formed to provide the above-described curved fitted yoke having upper and lower edges of unequal lengths. When the scarf is draped around the neck, as illustrated in Figure 3, the unequal lengths of the upper and lower edges of the sections 10 and 11 of the yoke will cause the yoke to conform closely to the back of the neck and fit thereto with the edges 10d and 11d of these sections coinciding substantially with the top of the shoulders. Inasmuch as the edges 12b and 13b of the sections 12 and 13 are curved inwardly, their normal tendency is to overlap with the sections 12 and 13 lying smoothly over the chest.

From the preceding description, it will be apparent that scarves of the type embodying the present invention are constructed and arranged to conform to the shape of the neck and the shoulders so that they will lie smoothly and fit closely around the neck and shoulders.

It will be understood further that the shape and dimensions of the various sections can be changed in order to fit individuals of varying size and to produce varying ornamental effects. Thus, for example, the sections 12 and 13 need not be provided with square corners, but instead can be tapered, rounded, scalloped, fringed, or otherwise ornamented, or shaped and, if desired, the pleats can be omitted from the top edges thereof. Such scarves may be formed of one or more layers of fabric and the fabrics may be of the same or dif-

ferent kinds and of the same or contrasting colors. Therefore, it should be understood that the form of scarf illustrated herein should be considered as illustrative, only, and not as limiting the scope of the following claims.

I claim:

1. A neck scarf comprising a plurality of sections of material joined end to end to form a center and two end portions, said center portion having one longer and one shorter edge and converging end edges, and said end portions having inclined edges joined to said converging end edges.
2. A neck scarf comprising a plurality of joined sections of material forming a center portion and opposite end portions, said center portion having one longer convexly curved edge, a shorter con-

cavely curved edge and converging end edges, and said end portions having inclined edges joined to said converging end edges.

3. The scarf set forth in claim 2 in which said center portion comprises two sections of material having joined concavely curved inner edges and aligned similarly curved side edges of different lengths.
4. A neck scarf comprising a plurality of joined sections of material forming a center portion and opposite end portions, said center portion having one longer convexly curved edge, a shorter concavely curved edge and converging concavely curved end edges, and said end portions having inclined edges joined to said converging end edges.
